his Attorney.

Patented Feb. 3, 1925.

UNITED STATES PATENT OFFICE.

EDWARD A. SCHOOLEY, OF DORMONT, PENNSYLVANIA.

RAILWAY SIGNAL TORPEDO.

Application filed August 6, 1924. Serial No. 730,443.

To all whom it may concern:

Be it known that I, EDWARD A. SCHOOLEY, a citizen of the United States, and resident of Dormont, in the county of Allegheny and State of Pennsylvania, have invented certain new and useful Improvements in Railway Signal Torpedoes, of which the following is a specification.

This invention relates to railway torpedoes used on railways as audible signals and more particularly to torpedoes embodying an explosive charge, an enveloping casing of fibrous material and a ductile metal strip for detachably securing the torpedoes to the rails of a railway track.

The principal object of this invention is to provide a novel form of enveloping casing composed of fibrous material, such as heavy paper, said casing being so formed that the torpedo may be readily and quickly assembled by unskilled workmen and thus reduce the cost of production.

Another object is to provide a novel manner of mounting the ductile metal retaining strip in the torpedo.

A further object is to provide a torpedo having the novel construction, design, and combination of parts hereinafter described and illustrated in the accompanying drawings.

In the drawings—

Figure 1 is a plan view of the body of the torpedo casing prior to assembling.

Figure 2 is a plan view of the reinforcing sheet carrying the metal attaching clip.

Figure 3 is a bottom plan of the torpedo with the lower flaps opened and the reinforcing sheet partly broken away to show the relation of the several parts.

Figure 4 is a sectional elevation of the assembled torpedo.

Figures 5 and 7 are views similar to Figure 3, of slightly modified constructions.

Figures 6 and 8 are sectional elevations of the modified forms of torpedoes shown in Figures 5 and 7, respectively.

Referring more particularly to the drawings which illustrate my invention, the letter A designates the enclosing fiber casing of the torpedo as a whole, which is formed from a flat piece of heavy paper or fiber board, cut in the form of a Maltese cross. The rectangular or square center 2 of the casing is depressed to form a concave depression 2^a for the reception of a preformed explosive tablet 3 and the arms of

the cross form flaps 4, 5, 6 and 7 adapted to be folded over the explosive tablet to close the casing. The flaps 4, 5, 6 and 7 are no more than half the width of the rectangular center so that when they are folded over the explosive tablet they do not overlap.

In each of the several forms of torpedoes illustrated in the drawings, a fiber reinforcing sheet 8 is mounted over the explosive tablet. The sheet 8 is rectangular in shape and of substantially the same size as the rectangular center 2 of the casing A. The sheet 8 is provided with a pair of slots 70 or apertures 9 through which a strip of ductile metal 10 is threaded, which strip is used to detachably hold the completed torpedo in position on the rail of a railway.

In the torpedo constructed as shown in Figures 3 and 4, the two diametrically opposite flaps 4 and 5 are first folded into position over the explosive tablet 3 and the reinforcing sheet 8 is mounted on top of these folded flaps. The remaining flaps 6 and 7 are then folded over the sheet 8 so as to hold it in position.

In the torpedo constructed as shown in Figures 5 and 6 the reinforcing sheet 8 is mounted directly over the explosive tablet 3 and the flaps 4 and 5 are bent over the sheet 8, these flaps being cut away as at 14 to fit around the ends of the ductile metal strip 10. The flaps 6 and 7 are folded or bent over the flaps 4 and 5.

In the torpedo constructed as shown in Figures 7 and 8, the reinforcing sheet 8 is mounted directly over the explosive tablet 3 and the ductile metal strip 10 has its ends projected through suitable apertures 12 formed at the junction of the flaps 4 and 5 with the center portion 2 of the casing. The flaps 4 and 5 are first folded over the reinforcing sheet 8 and then the flaps 6 and 7 are folded over the flaps 4 and 5.

In the formation of the torpedoes of this invention a coating of water-proof cement is applied to the concave depression 2^a prior to the insertion of the explosive tablet 3, and then a coating of the same cement is applied to the tablet 3 and surrounding portions of the center 2 of the casing to secure the flaps 4 and 5 or reinforcing sheet, which ever is positioned next to the tablet, and this operation is repeated until each successive part is firmly cemented to the preceding part, thus forming a rigid construction.

After the casing has been firmly cemented together the assembled torpedo is then placed in a suitable mold or die and pressed to finally compact the whole structure and complete the shaping thereof. After the torpedo has been pressed to final shape it is next coated with a suitable water-proofing compound, such as varnish, shellac, or the like, and then before such coating is dry, one or more sides of the torpedo are sanded and the sand will adhere to the sticky coating, thus forming an abrasive surface.

While I have shown and described several specific embodiments of my invention I do not wish to be limited thereto, since other modifications may be made without departing from the scope of my invention as defined in the appended claims.

20 I claim:

1. A fiber case railway torpedo comprising an enclosing case made in the form of a Maltese cross and having its rectangular center depressed to form a concave depression for holding the explosive tablet, the arms of said cross forming flaps for closing over the explosive and the length of said flaps being approximately one-half the width of the rectangular center portion so as to meet at the center lines of said cross when folded back over the explosive, a pre-formed explosive tablet mounted in said depression, a rectangular fiber reinforcing sheet of substantially the same size as said rectangular center located over said explosive tablet and held in position by said flaps, said reinforcing sheet being provided with apertures, and a ductile metal retaining strap threaded through said apertures and adapted to project materially beyond the sides of the finished torpedo, all of said parts being permanently secured together by quantities of water-proof cement.

2. A fiber case railway torpedo comprising an enclosing case made in the form of a Maltese cross and having its rectangular center depressed to form a concave depression for holding the explosive tablet, the arms of said cross forming flaps for closing over the explosive and the length of said flaps being approximately one-half the width of the rectangular center portion so as to meet at the center lines of said cross when folded back over the explosive, a pre-formed explosive tablet mounted in said depression, a rectangular fiber reinforcing sheet of substantially the same size as said rectangular center located over said explosive tablet, at least some of said flaps being folded over said reinforcing sheet to hold it in position, said reinforcing sheet being provided with apertures, and a ductile metal retaining strap threaded through said apertures and adapted to project materially beyond the sides of the finished torpedo, all

of said parts being permanently secured together by quantities of water-proof cement.

3. A fiber case railway torpedo comprising an enclosing case made in the form of a Maltese cross and having its rectangular center depressed to form a concave depression for holding the explosive tablet, the arms of said cross forming flaps for closing over the explosive and the length of said flaps being approximately one-half the width of the rectangular center portion so as to meet at the center lines of said cross when folded back over the explosive, a pre-formed explosive tablet mounted in said depression, two diametrically opposite ones of said flaps being folded over said explosive tablet, a rectangular fiber reinforcing sheet of substantially the same size as said rectangular center mounted on said folded flaps, the two remaining flaps of said case being folded over said reinforcing sheet, said reinforcing sheet being provided with apertures and a ductile metal retaining strap threaded through said apertures and adapted to project materially beyond the sides of the finished torpedo for use in securing the torpedo to a rail, all of said parts being permanently secured together by quantities of water-proof cement.

4. A fiber case railway torpedo comprising an enclosing case made in the form of a Maltese cross and having its rectangular center depressed to form a concave depression for holding the explosive tablet, the arms of said cross forming flaps for closing over the explosive and the length of said flaps being approximately one-half the width of the rectangular center portion so as to meet at the center lines of said cross when folded back over the explosive, a pre-formed explosive tablet mounted in said depression, two diametrically opposite ones of said flaps being folded over said explosive tablet, a rectangular fiber reinforcing sheet of substantially the same size as said rectangular center mounted on said folded flaps, the two remaining flaps of said case being folded over said reinforcing sheet, said reinforcing sheet being provided with apertures and a ductile metal retaining strap threaded through said apertures and adapted to project materially beyond the sides of the finished torpedo for use in securing the torpedo to a rail, all of said parts being permanently secured together by quantities of water-proof cement, and said completely assembled torpedo being coated over its entire outer surface with a water-proofing compound and having a coating of abrasive material over said water-proofing coating on at least one side thereof.

In testimony whereof, I have hereunto set my hand.

EDWARD A. SCHOOLEY.
